UNITED STATES PATENT OFFICE.

RALPH S. CLARKE, OF EAST WALPOLE, MASSACHUSETTS, ASSIGNOR TO BIRD MACHINE COMPANY, A CORPORATION OF MASSACHUSETTS.

PULP-SCREEN.

1,210,905.

Specification of Letters Patent. Patented Jan. 2, 1917.

Application filed May 29, 1916. Serial No. 100,687.

To all whom it may concern:

Be it known that I, RALPH S. CLARKE, a citizen of the United States, residing at East Walpole, in the county of Norfolk and State of Massachusetts, have invented new and useful Improvements in Pulp-Screens, of which the following is a specification, reference being had to the accompanying drawings forming part thereof.

10 This invention has reference to improvements in machines for screening or straining fibrous material, usually delivered to the machine as pulp, and particularly to that class of such pulp screening machines having rotary cylindrical pulp screens.

15 The invention relates more especially to mechanism for effecting the progressive rotation of the pulp gathering cylinders or screens to progressively carry the pulp gathered by said screens to positions to be acted upon by the water sprays, and to produce oscillatory action of the screen during such rotation to facilitate the passage of parts of the pulp through the screen.

20 One object of the invention is to construct a pulp gathering cylinder and the means for effecting oscillation thereof that intermittent rotation of the screen is effected as one result of said oscillation.

25 Another object of the invention is to improve the construction of the screen oscillating mechanism.

Other objects of the invention will appear from the following description.

30 The invention consists in the construction of the means for rotatably sustaining the pulp gathering screen.

35 The invention also consists in such other novel features of construction and combination of parts as shall hereinafter be more fully described and pointed out in the claims.

40 Figure 1, represents an end view of the improved pulp screening machine. Fig. 2, represents a plan view of the same. Fig. 3, represents an enlarged detail view of one of the arms or members for sustaining the screen.

45 Similar characters of reference designate 50 corresponding parts throughout.

As heretofore constructed pulp screening machines having cylindrical pulp gathering screens have been supplied with pivoted arms having bearings to receive collars of the screens. Rapid vibration of said arms 55 has been effected by cams and the reactive movements of said arms toward said cams has been resisted by buffers. In such machines additional provision has been made for rotatably driving the screens and more 60 or less complication has resulted therefrom.

In carrying this invention into practice I construct a pulp screen having the usual pulp receiving tank or pan 5 mounted on end frames 6, 6 which frames, in the present instance, have the members 7, 7 and 8, 8 which extend beyond the sides of said tank 5. On the members 7, 7 are mounted the upwardly extending arms 9, 9 which curve inward toward the vertical center of 70 the tank 5 and bearings 10, 10 the axes of which are substantially in horizontal alignment with the axis of the pulp gathering cylinder as will hereafter be pointed out. On the members 8, 8 are mounted the frames 75 or blocks 11, 11 carrying the lubricating devices 12, 12 and having bearings in which is journaled the cam shaft 13 furnished with the drive pulley 14 and with the cams 15, 15 to the periphery of which lubricant is 80 supplied from the devices 12, 12. These blocks 11, 11 have also the rods 16, 16 which are supplied with buffers or cushions 17, 17 of yielding construction or material against which the adjustable device constituted by 85 the nuts 18, 18 bears.

In the bearings 10, 10 of arms 9, 9 are journaled the pintles 19, 19 of the shaker arms 20, 20 which have curved ways 21, 21 having groups of seats 22, 22 and 23, 23 90 spaced apart and extending transversely of said ways 21, 21 to receive the bearing blocks 24, 24 and 25, 25 respectively. The forward or free ends of these arms 20, 20 have the transverse members 26, 26 and the projections 27, 27 to receive the riders 28, 28 which are secured to the members 26, 26 by the bolts 29, 29. In these arms 20, 20 are vertical guide perforations through which the rods 16, 16 extend so that the cushioning de- 100

vices 17, 17 are located between said arms 20, 20 and the nuts 18, 18 of the respective rods 16, 16 and act yieldingly against said arms 20, 20 to assist in overcoming the inertia 5 of said arms whereby said arms may react quickly from their upward movements caused by the elevations of the cams 15, 15 acting against the riders 28, 28.

The pulp gathering cylinder or screen 30 10 is of any usual construction adapted to gather pulp on its periphery and to permit the passage through its wall of the finer parts of said pulp. This cylinder or screen 30 has at its ends the collars 31, 31 which 15 are rotatably sustained by the bearing blocks 24, 24 and 25, 25, the diameters of these collars 31, 31 being such that the axis of said collars is approximately in alinement horizontally with the axis of the bearings 10, 10 20 of arms 9, 9.

Pulpy material, usually small particles of fibrous matter and water, is supplied to the pan 5 in any well known manner and this supply of pulp is maintained during the operation of the machine. The depth of this 25 pulp in the pan 5 is such that a large portion of the periphery of the cylinder 30 is in contact therewith and displaces a certain proportion of the pulp. As above indicated 30 the purpose of cylinder 30 is to gather pulpy material from the contents of said pan 5 and, in the rotation of said cylinder, to carry said gathered material beneath water to spray from the pipe 33 which spray acts to 35 wash the finer particles of pulp through the usual interstices of the screen of said cylinder, such passage of the particles of pulp being assisted by effecting the shaking or oscillation of the cylinder or screen.

40 By reference to Figs. 1 and 3 of the drawings it will be seen that the groups of bearing blocks 24, 24 and 25, 25 are so spaced apart on the ways 21, 21 of the shaker arms 20, 20 as to constitute substantially two 45 point bearings for the collars 31, 31 of the cylinder 30. While each of said groups of blocks is shown as having their bearing blocks 24, 24 or 25, 25, the number of said blocks in each group or bearing is not material 50 as the operation can be accomplished by one or more of said blocks in each group, the feature of main importance being that the collars 31, 31 are sustained at two points spaced apart and that said collars are free 55 to rotate and oscillate relative to said bearing points.

With a supply of pulp in pan 5 shaft 13 is driven at the desired speed and the cams 15, 15 act on their riders 28, 28 to effect the 60 vibration or oscillation of the free ends of arms 20, 20. As the free ends of these arms are suddenly thrown upward a similar motion is given to the collars 31, 31 of the screen or cylinder 30, action of the blocks

24, 24 against said collars 31, 31 being somewhat greater than the action of the blocks 65 25, 25 thereon owing to the respective spacing of said groups of blocks from the pivots 19, 19 and their bearings. In effect the rapid upward impulses of the blocks 24, 24 70 against the collars 31, 31 tends to drive said collars upward out of contact with said blocks 24, 24. At or about the upward movement of said arms 20, 20 the cushioning devices 17, 17 begin to act to overcome 75 the inertia of said arms 20, 20 while the inertia of the screen or cylinder is overcome mainly by gravity so that the free ends of arms 20, 20 react more quickly than the screen or cylinder 30. Also, it is to be understood, 80 that the reactive (downward) movement of the screen or cylinder 30 is resisted somewhat by the mass of pulp in the pan 5. The continued vibratory action of arms 20, 20 will therefore effect both the 85 vibration of the screen or cylinder 30 and at the same time an intermittent progressive relation thereof in the direction indicated by its arrow.

I prefer to make the blocks 24, 24 and 25, 25 of wood and to seat them as shown in the drawings so that said blocks, when they become worn, may be driven from their seats and replaced by new blocks.

By the use of the novel mounting for the 95 rider or striker members 28, 28, these members can conveniently be renewed from time to time.

I find it desirable to supply oil or other lubricant to the cams 15, 15 during the operation of the machine to maintain a good lubrication between said cams and their riders or strikers 28, 28.

Having thus described my invention I claim as new and desire to secure by Letters 105 Patent.

1. A pulp screening machine comprising a frame, a pulp receiving pan sustained by said frame, arms and blocks on said frame arranged in pairs at the respective sides of 110 said pan, a shaft journaled in said blocks and having cams, screen carrying members pivotally mounted on said arms and having screen supporting bearings spaced apart and elements bearing on said cams, a cylindrical pulp screen having collars sustained by said spaced bearings, said screen carrying members having perforations adjacent their free ends, rods mounted on said blocks and extending through said perforations, 120 yielding reacting buffers mounted on said rods above said members to resist the upward movement of said members and to exert reactive pressure thereon, and means at the upper ends of said rods to adjust the 125 pressure of said buffers.

2. A pulp screening machine comprising a frame having a pulp receiving pan and a

pair of arms extending upward at the ends of said pan, a pair of horizontal members pivotally sustained by said arms and having at their free ends horizontal abutments and 5 vertical webs, riding devices removably secured against said abutments and webs, said members having bearings to rotatably re-

ceive elements of a cylindrical screen, a pair of rotatable cams acting against said riding devices and yielding means acting to press 1 downward the free ends of said pivoted members.

RALPH S. CLARKE.
